BATTERY HANDLE

Robert M. Raney, Euclid, Ohio, assignor to Willard Storage Battery Company, Cleveland, Ohio, a corporation of West Virginia

Application October 24, 1952, Serial No. 21,970

Term of patent 14 years

(Cl. D26—6)

To all whom it may concern:

Be it known that I, Robert M. Raney, a citizen of the United States, residing at Euclid, in the county of Cuyahoga and State of Ohio, have invented a new, original, and ornamental Design for a Battery Handle, of which the following is a specification, reference being had to the accompanying drawing, forming a part thereof, in which

Fig. 1 is a perspective view of a battery handle showing my new design;

Fig. 2 is an end elevational view of the handle, looking from the left as viewed in Fig. 1; and

Fig. 3 is a rear view of the handle.

The broken line showing of a portion of a battery in Fig. 1 is for illustrative purposes only.

I claim:

The ornamental design for a battery handle, as shown and described.

ROBERT M. RANEY.
